CYRUS F. PALMER, OF UTICA, NEW YORK.

Design No. 4,847, dated April 25, 1871.

DESIGN FOR SCHOOL-DESKS AND SEATS.

The Schedule referred to in these Letters Patent and making part of the same.

To all whom it may concern:

Be it known that I, CYRUS F. PALMER, of the city of Utica, in the county of Oneida and State of New York, have invented or produced a new and original Design for Cast-Iron Ends for School-Seats; and I do hereby declare that the annexed photograph is a full and exact view of the same.

What I claim as my invention, and desire to secure by Letters Patent, is—

The application of this design, "made of cast-iron," to school-seats and desks.
